[57] CLAIM

The ornamental design for a pool table, as shown and described.

DESCRIPTION

FIG. 1 is a perspective view of a pool table showing our new design;

FIG. 2 is a front view thereof;

The rear view is a mirror image thereof;

FIG. 3 is a right side view thereof;

The left side view is a mirror image thereof;

FIG. 4 is a top view thereof; and,

FIG. 5 is a bottom view thereof.

The broken line showing of balls is for illustrative purpose only and forms no part of the claim.
